UNITED STATES PATENT OFFICE.

JAMES C. DAWSON, OF ST. LOUIS, MISSOURI, ASSIGNOR TO SIEBER & TRUSSELL MANUFACTURING COMPANY, A CORPORATION OF MISSOURI.

LOOSE-LEAF BINDER.

No. 893,312.

Specification of Letters Patent.

Patented July 14, 1908.

Application filed March 14, 1908. Serial No. 421,252.

To all whom it may concern:

Be it known that I, JAMES C. DAWSON, a citizen of the United States, and resident of the city of St. Louis, State of Missouri, have 5 invented certain new and useful Improvements in Loose-Leaf Binders, of which the following is a specification and which are illustrated in the accompanying drawings, forming a part thereof.

10 The invention relates to loose leaf binders and particularly to such binders wherein a plurality of filing rods are provided for receiving the sheets to be bound and in which the covers of the binder are preferably structurally independent of each other, one of such 15 covers constituting a base upon which the filing rods are permanently mounted adjacent its rear or binding edge and the other cover being a follower for running on the rods. 20 The object of the invention is to provide improved means for removably securing the follower of such binders in any adjusted position upon the filing rods and the invention 25 contemplates a filing rod, a follower running on the rod and a lever pivotally mounted on the follower and having a yielding cam face for engaging the rod.

In the accompanying drawings:—Figure 1 is a detail side elevation of a loose leaf binder 30 embodying the features of the invention, some of the parts being shown in section and the plane of the section being indicated by the line 1—1 on Fig. 2; Fig. 2 is a detail plan view of the same some of the parts being 35 broken away; Fig. 3 is a detail sectional view taken on the line 3—3 of Fig. 1; and Fig. 4 shows in plan a cam lever employed in the device separated from the other parts.

40 The covers of the binders are designated by the numerals 10 and 11. Preferably each is made flexible along a line extending completely across its surface a short distance from its rear marginal edge as indicated at 12 to permit of the swinging of the body portions of the covers for inspection of the leaves 45 of the binder. As shown each of the covers is overturned at its rear edge to provide overlapping plates 13, 14 for closing the back of the binder.

50 Filing rods, 15, 16, which may be as numerous as the size of the leaves to be bound requires, two such being shown, have their bases firmly secured to one of the cover members as 10, adjacent its rear edge preferably 55 by being riveted thereto as indicated at 17.

In order that the length of the filing rods 15, 16, may be adapted to the number of sheets required to be bound these rods are most conveniently made sectional, the outer end of each section being provided with a threaded 60 socket 18, for removably receiving the reduced and threaded inner end, 19, of each succeeding section as 20.

The leaves X to be bound and the cover member 11, are provided with apertures 65 21, for receiving the filing rods, 15, 16, and means are provided for securing the cover member 11 in position upon the rods 15, 16, above the leaves in order that the latter may be firmly clamped in position upon the filing 70 rods between the two cover members. To this end a cam lever 22, is pivotally mounted upon the cover member 11, adjacent each of the apertures 21 provided for receiving the filing rods, for engaging these rods. A bearing 75 plate 23 permanently secured to the cover member 11, as by rivets 24, 25, serves for carrying each of the levers 22. As shown a portion, 26, of this plate is overturned upon the body of the plate to provide a support 80 both above and below the lever 22 for the pivot 27 of the lever and a protective housing 85 for one end of the lever, the body portion and the overturned portion 26, of the plate being both apertured in line with the aperture 21 of the cover member for receiving the filing rod.

A thumb piece 28 is formed upon one end of each of the levers 22 and at the other end a yielding cam finger, 29, is provided for engaging one of the filing rods, preferably by notching the lever at 30, as most clearly shown in Fig. 4 of the drawings. Preferably the open end of the notch 30, is remote from that part of the cam finger 29, which first 90 engages with the filing rod in order that the cam finger may be more yielding at that point where the greatest pressure is applied. When constructed in this way no permanent set will be given to the cam finger even 95 though it be caused to bind upon the filing rod with great force. Most conveniently the levers, 22, are of such a form and are so mounted upon the cover member 11, that they extend in a direction substantially in 100 line with the binding edge of the book when they are caused to engage with the filing rods 15, 16, and they are thus out of the way when the covers of the binder are thrown back for an inspection of its leaves. To pre- 105 110

vent the desk of the user from being marred by the filing rods 15, 16, the protruding end of each of these rods is covered by a rubber cap, 31.

- 5 In use the cover member, 11, of the binder may be removed from the filing rods 15, 16 (caps 31 having been first taken off) if the levers 22, be turned to a position in which the cam fingers 29 become disengaged from the filing rods. Additions to or rearrangement of the leaves X may then be made and the leaves be again firmly clamped between the covers by the application of the cover member 11 to the filing rods immediately 10 above the last sheet inserted and by a swinging of the levers 22 to engage the filing rods for firmly securing the cover member 11 in position thereon.
- 15 I claim as my invention:—
- 20 1. In a loose leaf binder in combination, a base, a filing rod rising from the base, a follower running on the rod, and a cam lever pivotally mounted on the follower to bear on the rod, such lever being channeled to permit of a yielding of the cam.
- 25 2. In combination, a filing rod, a follower running on the rod, and a lever pivoted to

the follower to swing in a plane transverse to the axis of the rod, such lever having a rounded contact face for engaging the rod 20 and being notched, the notch being adjacent the contact face and extending substantially parallel thereto.

3. In combination, a filing rod, a follower running on the rod, and a lever pivoted to 35 the follower to swing in a plane transverse to the axis of the rod, such lever having a rounded contact face for engaging the rod and being notched, the notch being adjacent the contact face and extending substantially 40 parallel thereto, and the open end of the notch being remote from the point of the initial engagement between the contact face of the lever and the rod.

4. In a loose leaf binder, in combination, a base, a filing rod rising from the base, a follower running on the rod, and a cam lever pivotally mounted on the follower and having a yielding engagement with the rod.

JAMES C. DAWSON.
